DETACHING MOTION

Sigurd H. Helland, Whitinsville, Mass., assignor to
 Whitin Machine Works, Whitinsville, Mass., a
 corporation of Massachusetts

Application May 16, 1942, Serial No. 443,299

8 Claims. (Cl. 19—120)

The object is the simplification of detaching motions for Heilman type combers in which the detaching and piecing mechanism operates alternately, forward and backward, to effect the detaching and piecing of the sliver. The invention resides in a system of intermittent or Geneva gear couples combined in such a way as to be capable of transmitting the required drive to the detaching rolls directly from the comb cylinder shaft, or any other shaft, with a minimum of associated gearing, a total of only three spur gears being all required in the ordinary case, and no differential gearing being employed in any event. In consequence of such simplification, the entire system can be most compactly organized in the comb, either under the sliver table or in the driving head enclosure, and the intermittent couples can be housed to work in an oil bath casing also of small dimensions, while in addition, the organization of the driven and driving members of the two couples adapts the detaching mechanism to be run at sustained speeds in excess of one hundred nips per minute, and without tendency to become noisy from wear. The principles of this organization are exemplified in the structure shown in the accompanying drawings, but without limitation to such or any particular form.

Fig. 1 is a side elevation of the whole unit, parts being in section;

Fig. 2 is a top plan with the casing cover removed; and

Figs. 3, 4, 5 and 6 represent four successive positions of the Geneva couples as assumed through one combing cycle, all taken on line II—II of Fig. 2 and looking in the direction of the arrow.

It will be understood that the comb cylinder shaft, marked 1, is driven in any suitable way, not shown, and extends from the drive-head at one end of the comb through the row of comber-heads and carries the respective comb cylinders for such heads, and that the detaching roll shaft, marked 2, also extends from the drive-head through all of the comber-heads wherein it forms or carries the lower detaching rolls 3, for each combing-head, such rolls being associated with top rolls 4 as indicated in Fig. 1. In the present case there are two detaching roll shafts, the front roll shaft being driven from the back roll shaft by means of an intermediate long-tooth idler 5 engaging both, this being a usual construction.

It will be understood also that according to the conventional combining operation the forward

end of a periodically advanced lap, of cotton or other fiber, after being combed by the comb cylinder is presented to the back detaching rolls 3 and 4. These rolls then rotate forwardly so as to detach the tuft from the lap. They then rotate reversely so as to extend the rear end of the tuft rearwardly to a less extent than the forward rotation to have the head end of the next following tuft overlapped upon it, in the next cycle, thus accomplishing the piecing action, all of this being the customary operation of combing machines of this type and not illustrated on this account. The backward rotation in the present case is exactly half of the forward rotation but can be made any fraction by appropriate change of design, and as will presently appear.

The back detaching roll shaft 2 is driven by its pinion 6 from a spur gear 7 fast on a lay shaft 8 journaled in the casing of the unit. Such casing can be mounted on any appropriate bracket or support and is intended to hold a body of lubricant. Within this casing the shaft 8 carries fast upon it the driven or star-wheel element 9 of a Geneva couple, and it is by this couple that the detaching roll shaft is driven in its forward direction. Also within the casing the shaft 8 carries fast upon it a spur gear 10 meshing with a pinion 11 journaled on a stud 12 fixed in the side wall of the casing. This pinion is compounded with the driven or star-wheel member 13 of the second Geneva couple, the function of which is to drive the shaft 8 in the direction that rotates the detaching roll shaft 2 in the reverse direction.

Both star-wheel elements are thus geared to each other so that rotation of one rotates the other, and rotation of either rotates the detaching roll shaft independently of the other and both are enclosed in the casing, facing each other, that is to say, one is adjacent one side of the casing, and the other adjacent to the opposite side, with a space between them.

The driving means for both star-wheel members operates in the space between them and is represented in the present case by a sleeve 14 which is keyed or otherwise fixed upon the comb cylinder shaft 1, and carries two crank arms and a locking segment 17. The longer arm carries the Geneva driver-stud 15 (and roller) for the star-wheel member 9, and the shorter arm carries the corresponding Geneva stud 16 (and roller) for the other star-wheel 13. The studs point in opposite directions from their respective arms and are adapted for entering the radial slots in their respective star-wheels thus to

turn them, as customary in Geneva couples. The two arms engage their wheels in alternation and are so angularly related that when one is actively engaged with its star-wheel, the other one is disengaged from its star-wheel. The locking segment 17, constituting part of the control means of the forward-driving star-wheel is adapted to enter and lock with the segmental notches 18 formed in the rim of the star-wheel 9, to hold it against rotation, and is of such length and angular position on the sleeve 14, that it enters one of said notches at the moment the long arm stud 15 leaves or disengages itself from one of its star-wheel slots, having completed its turning action thereon; that is to say, having turned the star-wheel 9 forwardly to the extent required for the forward rotation of the detaching roll shaft, the segment then locks that star-wheel against any tendency to rotate from any cause or reaction. Unlike other Geneva couples, however, the segment 17 is arcuately short and rotates out of its notch before the driver stud 15 again comes into action so that the star-wheel 9 is then unlocked. This occurs at the moment the other driver stud 16 enters its star-wheel and during the unlocked period the latter stud has control. Its action on its star-wheel is to rotate the shaft 8 and hence the detaching roll shaft in the reverse direction. It also rotates the unlocked star-wheel 9 reversely and to just the extent required to bring one of its radial slots in line with the path of stud 15 so that the latter can enter such slot. This Geneva member 16 has no locking segment.

The sequence of positions is indicated in Figs. 3-6. Fig. 3 shows the forward driving stud 15 at the point of entering one of the slots or channels of its forward driving star-wheel 9. This is at the beginning of the forward detaching roll rotation and at this instant the reverse driving stud 16 is on the point of leaving its slot in the reverse-driving star-wheel 13.

Fig. 4 represents the positions of the same parts after the forward rotation has been half completed. The forward driving stud 15 is now engaged in rotating its star-wheel 9 in the direction of the arrow. At this time the other star-wheel 13 is not engaged by its driver and is being rotated reversely to its driven rotation as indicated by the arrow, such reverse rotation being in consequence of its connection to the shaft 8 by the gear couple 10-11. The locking segment 17 has not yet entered a rim notch 18.

In Fig. 5 the stud 15 has completed its action on its star-wheel 9, being on the point of leaving the slot thereof, and the locking segment 17 has entered one of the rim notches 18. It is thus holding both star-wheels stationary and of course the detaching mechanism. This dwell of the detaching mechanism, as will be seen, occurs at the end of the forward stroke, as customary, and continues until the segment 17 leaves its notch.

Fig. 6 shows the parts at this instant. The short arm stud 16 is now entering one of the slots in its reverse-driving star-wheel 13 and about to rotate the latter in the direction indicated by the arrow in Fig. 6, which as stated reversely rotates the shaft 8 and the parts geared to it bringing the parts back to the position of Fig. 3.

In the present case the star-wheels are each rotated a quarter turn by their respective driver studs, and by virtue of the 2 to 1 ratio of gears 10 and 11 this results in a $\frac{1}{8}$ reverse rotation

of wheel 9 on each cycle. Accordingly this wheel is provided with eight slots for engagement by the stud 15 while the reverse star-wheel 13 has only four. Thus it may be observed that the star-wheel slot marked *a* in Fig. 3, moves to the position of the channel marked *c* in that figure by the end of the $\frac{1}{4}$ forward rotation, and is then moved back to the position of the channel marked *b* in that figure at the end of the reverse rotation, being at such time correctly placed to receive the stud 15 on its next arrival, as indicated by Fig. 6. In like manner the channel of the other star-wheel 13 marked *d* in Fig. 3 makes one-half revolution, during the forward action, assuming the position indicated in Fig. 5 at the end of such action, which places it in readiness to receive its stud 16. After that stud has acted upon it, it occupies the position of channel *e* in Fig. 3.

20 I claim:

1. In a textile comber the combination of the comb shaft, the detaching roll shaft and detaching motion for connecting the detaching roll shaft to the comb cylinder shaft comprising two Geneva couples having separate driven star-wheel members, a casing enclosing said couples and into which said comb cylinder shaft extends, a lay shaft also in said casing the driven members of such couples being operatively connected to said lay shaft within said casing and a gear on said lay shaft outside of said casing operatively connecting it to said detaching roll shaft, the driving members of such couples being mounted on the comb cylinder shaft within said casing, and adapted for alternately engaging said driven members for rotating said lay shaft backwardly and a greater distance forwardly on each rotation of said comb shaft.

2. In a textile comber, the combination with a drive shaft and a detaching roll shaft, of a detaching motion for advancing said roll shaft with an alternating motion, comprising gearing intermediate of and connecting said shafts including the two star-wheel members of two Geneva couples, said star-wheel members being mounted in positions facing each other and means on the drive shaft mounted to work in the space between said two star-wheel members, for engaging and driving them in alternation.

3. In a textile comber, the combination with a comb shaft and a detaching roll shaft, of a detaching motion for alternately forwardly rotating said detaching roll shaft and backwardly rotating it to a less extent, comprising two Geneva couples having their star-wheel members geared together in one-to-two ratio and facing each other and both connected to drive said detaching roll shaft, a Geneva stud for rotating one of said star-wheel members in one direction, a Geneva stud for rotating both said star-wheel members in the opposite direction and a drive-head on said comb shaft carrying said stud members for said star-wheels in the space between them, and adapted for alternately driving them.

4. In a comber the combination with the comb shaft, and the detaching roll shaft of a detaching motion for advancing said roll shaft with a forward and backward motion, comprising two Geneva couples having their star-wheel members geared together, a driving and controlling member for one of said star-wheel members comprising a Geneva stud and a locking segment, a driving member for the other star-wheel member comprising a Geneva stud but no locking segment, means on said comb shaft for revolving

said studs alternately into engagement with their respective star-wheel members, and a gear connecting said members to the detaching roll shaft.

5. The combination in a textile comber with a comb shaft and a detaching roll shaft of a detaching motion for alternately forwardly and backwardly rotating the detaching roll shaft comprising two geneva couples having their star-wheel members geared together, both being geared to said detaching roll shaft, a Geneva stud and locking segment for controlling one of said star-wheel members, a Geneva stud but no locking segment for controlling the other and a rotary drive head on said comb shaft carrying said studs and revolving them into alternate engagement with their respective star-wheel members.

6. In a comber the combination with the comb shaft and detaching roll shaft, of a detaching motion for driving the latter shaft comprising two Geneva couples, two-to-one gearing between the star-wheel member of one of said couples and the star-wheel member of the other couple, both said members being geared to said roll shaft, Geneva studs for said members, means for rotating said studs in the same direction and into alternate driving engagement with their respective star-wheels, said studs being so angularly related to each other that as each leaves its star-wheel slot, the slot of the other star-wheel member is in position to receive the other stud, and a

connecting gear between said star-wheel members and the detaching roll shaft.

7. In a comber the combination of a rotary comb cylinder shaft, a detaching roll shaft and a detaching motion connecting the latter shaft to the comb cylinder shaft as its source of power and comprising two star-wheel members both constantly in geared driving connection with said detaching roll shaft for respectively rotating it in opposite directions and a pair of arms fast on the comb cylinder shaft carrying driver studs respectively cooperating with said star-wheel members to impart a greater forward than backward rotation to said roll shaft.

10 15 20 25

8. In a textile comber, the combination with a comb shaft and a detaching roll shaft, of a detaching motion for alternately forwardly rotating said detaching roll shaft and backwardly rotating it to a less extent, comprising two radially-slotted star-wheel members geared together and to said detaching roll shaft, and two driver studs for respectively engaging the slots of said members for rotating them, said studs being carried by the comb shaft and angularly spaced thereon to engage their respective star-wheel slots in alternation, and a locking segment on said comb shaft engaging one of said members in the interval when neither of said studs is engaged therewith.
